UNITED STATES PATENT OFFICE.

FRANCIS MEISEL, OF BOSTON, AND HERBERT L. CHAPIN, OF CHELSEA,
MASSACHUSETTS, ASSIGNORS TO SAID MEISEL.

WEB-PERFECTING PLATEN PRINTING-MACHINE.

SPECIFICATION forming part of Letters Patent No. 514,563, dated February 13, 1894.

Application filed December 9, 1892. Serial No. 454,604. (No model.)

To all whom it may concern:

Be it known that we, FRANCIS MEISEL, of Boston, and HERBERT L. CHAPIN, of Chelsea, in the county of Suffolk, State of Massachusetts, citizens of the United States, have invented certain Improvements in Web-Perfecting Platen Printing-Machines, of which the following is a full, clear, and exact description, reference being had to the accompanying drawings, making part of this specification, in which—

Figure 1 is an elevation of one side of our improved printing machine. Fig. 2 is a sectional end elevation of the same on the line 15 2 2 of Fig. 1. Fig. 3 is a sectional elevation on the line 3 3 of Fig. 4. Fig. 4 is a sectional plan view on the line 4 4 of Fig. 3. Fig. 5 is a side elevation of the form-roller track and its operating mechanism. Fig. 6 is a plan of 20 the same. Fig. 7 is an elevation of one side of the platen, showing the tympan-frame and mechanism for operating the same. Fig. 8 is a plan view of the same. Fig. 9 is an enlarged view of the parts shown in Fig. 7. Fig. 10 is 25 a plan of the same. Fig. 11 is an enlarged sectional detail showing one of the lips or flanges of the platen upon which the tympan frame slides. Fig. 12 is a detail view of the top feed-roll mechanism. Fig. 13 is an end 30 view of the same. Fig. 14 is a plan view of the machine. Figs. 15 and 16 are elevations of two of the cams which operate the toggles. Figs. 17, 18, and 19 are details of the mechanism by means of which the form-rollers are 35 operated to ink the type-forms.

Our invention relates to that class of platen printing-machines where the paper is taken from a continuous web or roll, and in which two type-beds and two platens are employed; 40 and our invention consists in certain novel combinations of parts and details of construction as hereinafter fully set forth and specifically pointed out in the claims.

In the said drawings, A represents the frame- 45 work of the machine, on the base of which between the side pieces is mounted a stationary plate B, forming a type-bed, and between the upper ends of the said side pieces is secured a stationary plate C, forming a platen and

arranged directly over and in line with the 50 stationary type-bed B.

D is a vertically reciprocating plate, forming a type-bed which co-operates with the upper stationary platen C, and E is a vertically reciprocating plate forming a platen, 55 which co-operates with the lower stationary type-bed B, said platens and type-beds being all arranged vertically in line with each other. On these type-beds B, D, the type-forms are 60 imposed in the usual manner.

The reciprocating type-bed D and reciprocating platen E are provided at their opposite ends with arms 19 guided in vertical grooves in the framework A, and are connected together in such manner as to move 65 simultaneously in opposite directions by means of two double toggles G, G, Figs. 1 and 3, the construction and operation of which will now be described. Each of said double toggles is composed of a central oscillating 70 bar or member b, provided at its ends with central journals c, adapted to oscillate in bearings in the framework A, the upper and lower edges of the members b being jointed respectively at d, e, to the upper and lower members 75 g, h, of the double toggles, the former g, being jointed at i to the reciprocating type-bed D, and the latter h, at k to the reciprocating platen E, whereby as the two members b, b, 80 are rocked on their centers c, the upper and lower toggles will be operated as desired. The two upper toggle joints d, d, are connected by a horizontal bar l and the two lower toggle joints e, e, are similarly connected by a horizontal bar m, said bars serving to transmit the power from one toggle to the other. The central members b, b, of the toggles are each provided with two inwardly projecting arms p, p, one near each end, as shown in 85 Figs. 3 and 4, said arms carrying cam rolls q 90 which are acted upon by cams r, r, s, s, on the main or central shaft I, whereby as said shaft is rotated, the double toggles are closed or straightened out, as shown in Fig. 3, and the movable type-bed and movable platen, 95 which are nearly of the same weight, moved simultaneously in opposite directions to cause them respectively to co-operate with the sta-

60

tionary platen and stationary type-bed to produce the impressions, a single revolution of the central shaft I producing two impressions, one on each side of the sheet, as required in 5 a perfecting press.

By using the upper stationary plate C as a type-bed, and the plate D immediately thereunder as a platen, it will be obvious that the machine can be adapted for color printing, 10 and two colors can, by this arrangement, be printed in succession on one side of the sheet.

Outside the framework A the shaft I is provided with two cams *t*, *u*, which act upon cam rolls *w*, *a'*, at the outer ends of crank arms *b'*, *c'*, 15 secured to the journals *c* of the central toggle members *b*, and serve to rock said members *b* in a direction opposite to that in which they are moved by the cams *r*, *s*, thus opening the toggles as shown dotted in Fig. 1, and returning 20 the parts to their normal positions. The several cams above described are so formed and timed as to permit the reciprocating type-bed and reciprocating platen to remain at rest during such time as is required for the forms 25 to be inked and the paper to be drawn through the machine for the succeeding impressions by mechanism to be hereinafter described. By thus combining a vertically reciprocating platen co-operating with a stationary type-bed and a vertically reciprocating type-bed co-operating with a stationary platen with 30 toggle mechanism arranged directly between and connected with said reciprocating platen and reciprocating type-bed and adapted to 35 move the same simultaneously in opposite directions as above described, the power exerted by the toggles is enabled to do double the work, as we are enabled to utilize the force hitherto exerted in a downward direction 40 against the stationary base or bed to which the lower toggle member has been jointed, and which has hitherto been wasted or rendered unavailable; that is, the downward pressure exerted by the lower member 45 of a toggle against a stationary bed or base is, by our construction and arrangement of parts now made available to do the work of printing by connecting the lower platen therewith, and as the weight of the reciprocating 50 platen is about equal to that of the reciprocating type-bed, it will be obvious that they will balance each other in their alternate ascent and descent, the weight of the one in its descent counterbalancing and assisting to 55 raise the other in its ascent, whereby the power required to operate the machine is reduced to a minimum, and a great saving thereby effected.

To the main or central shaft I is secured a 60 large gear K which is driven by a pinion *v* shown dotted in Fig. 1, on the driving shaft L, the latter carrying as usual a fly or balance wheel and fast and loose pulleys, not shown.

We will now describe the inking apparatus 65 by means of which the forms are inked after each impression is taken. Each of the type-forms is inked by a series of form-rollers *d'*,

Figs. 1, 5, and 6, the journals or shafts of which run in bearings in carriages X, shown in Figs. 17, 18, and 19, said carriages being 70 adapted to run on horizontal bars M, M, which form tracks or guideways therefor. The bars M are supported by rocker arms *e'* pivoted thereto and secured to rocker shafts *f'*, *g'*. The shaft *f'* of the upper form roller track is provided with a crank arm 15, to which is pivoted a connecting rod 16 carrying a cam roll *h'*, which is acted upon by a cam wheel N on the main shaft I, the lower end of the rod 16 having formed thereon a forked guide *i'*, which 80 embraces and slides upon the shaft I, by which it is supported. The shaft *f'* is also provided with a crank arm *k'* which is connected by a rod *l'* with a crank arm *m'*, Fig. 1, on the shaft *f'* of the lower track M, whereby as the connecting rod 16 is actuated by the cam wheel N, both of the tracks M, M, 85 will be simultaneously raised and lowered at the proper times. When the tracks M are lowered, the form rollers will be at the proper level to take ink from the distributing rolls or ink cylinders P at opposite ends of the tracks, and when these tracks are raised to their highest position, the form rollers will be at the proper level to ink the type forms. 90 By this construction we are enabled to place the ink cylinders P below the level of the tracks M, thereby avoiding the wear which would otherwise be occasioned by the form rollers riding up over the ink cylinders if the 95 tracks M were not capable of being raised and lowered; it being obvious that if the said tracks were stationary, it would be necessary to have the ink cylinders project above the 100 level of the tracks in order that the form rollers might be brought into contact therewith. The form rollers are moved forward and back over the type-forms to ink the same in the following manner. To each of the form roller carriages X is secured a pair of horizontal 105 rack-bars 75 shown in Figs. 17 and 18, which slide in suitable grooves in the framework and are actuated by gears 76 secured to a horizontal shaft 77 to which is also secured at one end a pinion 78. These two pinions 110 115 of the upper and lower shafts 77 are both engaged by a vertical rack-bar 79 moving in suitable guides and having pivoted to it at 80 a connecting rod 81, the opposite end of which is pivoted to a lever 82 fulcrumed at 115 83 to the framework and carrying a roll 84 which runs in a cam-groove 85 in a cam-wheel 86 fast on a shaft 87 which carries at one end a bevel-gear 88, shown in Fig. 18, with which meshes a smaller bevel-gear 89 on a shaft 90 120 carrying at its opposite end a bevel-gear 91 which is driven by a bevel-gear 92 on the main shaft I, the gears being so proportioned that two revolutions of the shaft I are required to produce a single revolution of the 125 cam-shaft 87. The form rollers *d'* are thus moved forward and back over the type-forms to ink the same at each complete revolution of the cam-wheel 86, the cam-groove 85

of which is properly shaped to produce the necessary dwell at the termination of the traverse of the form-rollers in either direction. The shafts of the form rollers are forced downward to keep said rollers in contact with the type-forms by means of spiral springs 95, as shown in Fig. 19.

The roll of paper Q is mounted on a horizontal shaft, the journals of which rest in suitable bearings in the framework, as shown in Fig. 1. The web of paper R from this roll Q passes over guide-rods 20, 21, and under a rod 22, thence horizontally between the reciprocating platen E and the stationary type-bed B, thence under a guide-rod 23 and over a guide and take up roller 24 and horizontally between the upper stationary platen C and the reciprocating type-bed D, after which it passes under a horizontally adjustable guide-rod 25 to the feed or drawing rolls 26, 27, 28, between which it is tightly gripped and by which it is fed or drawn forward intermittently after the impressions have been taken; the length of paper drawn forward at each operation of the feed rolls corresponding to that of a single detached sheet after it is printed. The shaft of the lower or main feed roll 26 is provided with suitable well known mechanism not shown, whereby it is rotated intermittently at the proper times as required. The upper feed rolls 27, 28, bear upon the margins of the paper as usual, these rolls being moved solely by the frictional contact of the lower feed roll 26 with the paper between said roll 26 and the rolls 27, 28. The shafts 29, 30, of the rolls 27, 28, are mounted in curved arms n' projecting from a horizontal shaft p', the shafts 30 of the rolls 28 being supported in fixed bearings at the outer ends of the arms n', and the shafts 29 being supported in boxes 31, Fig. 12, adapted to slide within slots in the arms n', each box having behind it a spiral spring 32, which acts to force the roll 27 constantly toward the lower roll 26. To one end of the shaft p' is secured an arm q', to the lower end of which is pivoted a rod r' having a screw thread at its outer end, over which is fitted a threaded sleeve s', provided at one end with a hand wheel 33, and at its opposite end with a conical point which enters a correspondingly shaped recess in a bearing block 34, whereby by turning the screw sleeve s', the rolls 27, 28, may be made to bear with more or less force upon the paper passing over the feed roll 26, the springs 32 behind the rolls 27 causing the latter to bear upon the periphery of the roll 26 with approximately the same force as the rolls 28, and by thus arranging a series of pressure rolls to bear at different points around the circumference of the main feed roll, instead of in a single line only, the hold or frictional contact of the rolls upon the paper is materially increased, and the positive feed of the web thereby insured, as all liability of slip is avoided. As the web R is stretched tightly under the surface of the

lower or reciprocating platen E when the latter descends to produce the impression, it will be evident that it would become slack on the ascent or return movement of said platen, hence it becomes necessary to employ a take-up device, which I will now describe. The journals of the guide-roll 24 are mounted in bearings in blocks t' made adjustable upon horizontal bars S, Figs. 1 and 14, one on each side of the machine; said bars being arranged to slide horizontally in suitable guideways on the frame A. Each bar S is provided on its upper side with rack teeth w', with which engages a toothed sector a², secured to a horizontal rock shaft 18 having its bearings in the framework, and provided outside the framework with a slotted arm b², to which is adjustably secured a rod c², the lower end of which is jointed to an arm d² pivoted to the framework, said rod c² at its junction with the arm d² carrying a cam roll e², which fits within and is acted upon by a cam groove T on the inner face of the main gear K, and thus through the connections described, as the shaft 18 and toothed sectors a² are rocked in the proper direction, the horizontal bars S will be forced outward in the direction of the arrow, Fig. 1, thus causing the roller 24 to take up the slack of the web R as the platen E rises, and keep it tightly stretched in its proper position against the under surface of the said platen, the movement of the bars S being properly timed to correspond with its upward and downward movement. When that portion of the web R between the guide rod 23 and the guide and take-up roller 24 assumes different angles, as occurs when said web is to be cut up into sheets of different lengths, the take-up roller 24 is adjusted on the bars S to produce the proper register of the two impressions on opposite sides of the sheet, and at the same time the pivot of the rod c² is adjusted in the slot of the arm b² to vary the amount of movement of the bars S to cause the roll 24 to properly take up the slack of the web; it being necessary to increase the movement of the bars S in proportion as the roll 24 is moved on the said bars S toward the center of the machine.

We will now describe the tympan-frame and its operative mechanism by which it is raised and lowered to bring the tympan-sheet tightly up against the surface of the platen, and lowered to enable said sheet to be easily drawn out from under the "blanket."

Each platen has a tympan-frame W, Figs. 7, 8, 9, 10, and 11, which is provided with lugs f², g², having inwardly projecting pins 35, 36, which are adapted to fit or hook over and slide upon the lips or flanges h² at each end of the platen as seen in Fig. 11, said flanges thus forming guides or tracks which support the tympan-frame W, and upon which it is slid in and out as occasion may require. The tympan-sheet i² is secured as usual to the cross bar 52 at the inner end of the tympan-frame and has its opposite end fastened to

a rotary take-up bar k^2 , Fig. 9, provided at one end with a retaining ratchet and pawl, not shown, whereby the tympan-sheet is stretched tightly across the frame in the ordinary manner.

l^2 is a horizontal rock-shaft supported in bearings in lugs projecting from the platen, and to one end of this shaft l^2 is secured a bell-crank m^2 and to the opposite end an arm n^2 , the horizontal arm 50 of the bell crank m^2 and the arm n^2 being each cut away at the outer end on the upper side as seen at 37, forming a shoulder, shown dotted; said shoulders forming stops, against which the pins 36 are brought into contact when the tympan-frame is pushed in as shown dotted in Fig. 9, in which position the pins 36 rest upon the cut-away ends of the bell crank lever m^2 and arm n^2 , and as the lugs g^2 are of greater length than the lugs f^2 , the tympan-frame will incline downward from front to rear when it is fully pushed under the platen, and consequently the bar 52 of the tympan-frame will not come into contact therewith as it is pushed in. To the upper arm of the bell crank lever m^2 is pivoted a rod p^2 provided at its opposite end with a handle q^2 and retaining notches r^2 , which engage a lug or projection s^2 on the platen to hold the bell crank in place when adjusted, and after the tympan-frame has been pushed in under the platen, the said bell-crank is rocked by pushing in the rod p^2 , which causes the arms 50, n^2 , on which the pins 36 rest, to raise up the tympan-frame into the position shown in full lines in Fig. 9, and thus bring the tympan-sheet tightly up against the under surface of the platen into its proper working position.

When it is desired to draw out the tympan-frame, the rod p^2 is pulled forward by means of its handle q^2 , thereby lowering the inner end of the tympan-frame and causing the tympan-sheet to drop away from the platen, when it can be easily drawn out, as required.

45 What we claim as our invention, and desire to secure by Letters Patent, is—

1. In an intermittent web-printing machine, the combination, with two reciprocating and two stationary plates or members arranged in pairs, one plate or member of each pair forming a platen and the other a type-bed, of toggle mechanism arranged between said reciprocating plates or members directly under the one and over the other, whereby the pressure is applied directly under and over the impression surfaces, said mechanism being arranged to separate or force the said reciprocating plates or members away from each other to produce the two impressions, substantially as set forth.

2. A web-printing machine having a lower stationary type-bed and an upper stationary platen arranged face to face, said type-bed being at the bottom and said platen at the top 65 of the machine, in combination with a lower vertically reciprocating platen co-operating with the lower stationary type-bed and an up-

per vertically reciprocating type-bed co-operating with the upper stationary platen, whereby the types on both type-beds are held face upward; said type-beds and platens being arranged in line one above the other, and the reciprocating platen and reciprocating type-bed being connected together by toggle mechanism arranged between said reciprocating platen and reciprocating type-bed directly under the latter and over the former, whereby the pressure is applied directly under and over the impression surfaces, said mechanism being arranged to separate or force the said reciprocating platen and reciprocating type-bed away from each other to produce the two impressions, substantially as set forth.

3. In an intermittent web-printing machine, the combination, with a vertically reciprocating platen co-operating with a stationary type-bed and a vertically reciprocating type-bed co-operating with a stationary platen, substantially as described, of connecting toggle-mechanism arranged between said reciprocating platen and reciprocating type-bed directly under the latter and over the former, whereby the pressure is applied directly under and over the impression surfaces, said mechanism being arranged to separate or force the said reciprocating platen and reciprocating type-bed away from each other to produce the two impressions, substantially as set forth.

4. In a web printing-machine, the combination, with a vertically reciprocating platen, co-operating with a stationary type-bed, and a vertically reciprocating type-bed co-operating with a stationary platen, substantially as described, of the toggles G, G , arranged between said reciprocating platen and reciprocating type-bed and serving to connect the same together whereby they are caused to move simultaneously in opposite directions, and balance each other, said toggles having central oscillating members b provided with arms p, b', c' , the central shaft I provided with cams r, s, t, u , adapted to act upon the arms p, b', c' , of the members b, b , to alternately open and close the toggles, substantially as described.

5. In a web printing-machine, the combination, with the reciprocating platen E, and a stationary type-bed B, of the toggles G, G , arranged between and connecting said platen and type-bed and having their central members b provided with arms p, b', c' , the central shaft I provided with cams r, s, t, u , adapted to act upon the said arms p, b', c' , to alternately open and close said toggles, and the horizontal rods l, m , connecting the upper and lower joints of one toggle with those of the opposite toggle, substantially as and for the purpose set forth.

6. In an intermittent web-printing machine, the combination, with the type-form, the form rollers d' , the ink or distributing cylinders and means for traversing the form-roller-carriage to bring the form-rollers over the type-form and then over the distributing cylinders,

of the vertically movable form-roller track or guide-way and means for raising and lowering said track to bring the form-rollers alternately into contact with the type-form and ink cylinders, substantially as described.

7. In a web printing-machine, the combination, with the form roller tracks M, of the rocker shafts f', g', provided with arms e' pivoted to the tracks M, and suitable connecting mechanism operated by a cam for oscillating the rocker shafts, whereby the tracks M are raised and lowered, substantially as and for the purpose set forth.

8. In a web printing-machine, the combination, with the co-operating type-beds and platens, of the take-up device for the web consisting of the horizontal sliding bars S carrying the web supporting roll 24, and means for reciprocating said sliding bars whereby the slack of the web is taken up at the proper time, substantially as set forth.

9. In a web printing-machine, the combination, with the co-operating type-beds and platens, of the horizontal sliding bars S provided with rack-teeth w' and carrying the web supporting roll 24, the rock shaft 18 with its toothed sectors a² and slotted arm b², the rod c², arm d², and the actuating cam T, all operating substantially as set forth.

10. In a web printing-machine, the combination, with the feed roll 26, of the shaft p' provided with arms n' carrying rolls 27, 28, the arm q', rod r', provided with the screw sleeve f', and the bearing block 34, all operating substantially as and for the purpose described.

11. In a web printing-machine, the combination, with the lower feed roll 26, of the rolls

28 mounted in fixed bearings at the ends of the arms n' of the shaft p', the rolls 27 mounted in yielding bearings in said arms n', the springs 32, the arm q' secured to the shaft p', the rod r' having the adjusting screw s', and the bearing block 34, whereby the pressure of the rolls 27, 28, on the paper can be regulated, substantially as set forth.

12. In a web printing-machine, the combination, with the sliding tympan-frame and the platen, of arms adapted to engage the said tympan-frame when pushed in to raise and lower the same, and means for operating the said arms, substantially as set forth.

13. In a web printing-machine, the combination, with the platen having lips or flanges h², of the tympan-frame W provided with lugs f², g², having inwardly projecting pins 35, 36, adapted to fit or hook over and slide upon the lips or flanges h², of the platen, the lug g² being longer than the lug f², whereby the tympan-frame is inclined downward from front to rear when pushed in, the rock-shaft l² with its bell crank m² and arm n², adapted to fit under the pins 36 of the tympan-frame, and the rod p² pivoted to said bell-crank and provided with a locking or retaining device, whereby the said bell-crank and arm are actuated to raise and lower the tympan-frame, and hold it in position, substantially as set forth.

Witness our hands this 5th day of December, A. D. 1892.

FRANCIS MEISEL.
HERBERT L. CHAPIN.
